UNITED STATES PATENT OFFICE

2,113,291

OVERHEAD DOOR CONTROL FOR A CLOSED
VEHICLE BODYCharles H. Clark and Robert C. Hollister,
Cortland, N. Y.

Application September 17, 1936, Serial No. 101,275

4 Claims. (Cl. 296—106)

Our invention pertains to an overhead door, particularly as applied to the rear of an automotive van or similar closed vehicle body, although certain of its more novel underlying principles find application to other purposes such as garage doors or the like.

As an exemplification, the present disclosure will primarily be directed to a tail end door of such body structure to command the entrance or exit to the van interior. Our sectionalized door may be of the so-called jack-knife construction having its upper marginal edge suspended by a master hinge from the transverse deck beam or lintel of a suitable doorway. Such door preferably comprises a pair of linked panels of which the lower element is arranged to fold upon an opened upper panel. When closed, the suspended door weight causes both panels to drop flatwise toward the cooperating jambs, said door being yieldably held against its jambs by supplementary retaining means.

A counterbalancing gear of the toggle linkage type including a non-extensible lifting bar facilitates swinging the door panels into three different positions with respect to the master hinge, namely: (a) closed or depending position, (b) horizontal or outrigger position, and (c) erect or upturned loading position. Said bar serves to counterbalance the lifted door between closed and outrigger positions and for automotive purposes, is spring loaded in preference to an equivalent suspended weight.

The present style of overhead door is also designed to swing erect with respect to the deck beam level to afford the maximum of head room under such lintel while a van is being loaded. A massive door of this kind is somewhat unwieldy to handle except when substantially counterbalanced in outrigger position. In order to prevent encroaching upon loadable van space, we preferably but not necessarily, locate our resilient counterbalancing means beneath the floor level and extend one end of a door lifting bar through the floor into cooperative engagement with such spring means. When loaded from a platform on a level with the van floor, said door when raised into erected position by the manipulation of our lifting bar, provides for unobstructed access into the vehicle doorway and thereby procures a clear gangway along the platform that shall be kept free from any overhead barrier likely to interfere with a speedy loading of the opened van.

The instant improvements constitute a continuation in part over our copending application, Serial No. 14,507 as filed April 3, 1935 and

which prior disclosure has herein been equipped with remote controls that permit of automatically opening our tail end door of a closed vehicle body from the driver's seat. To this end, we preferably resort to a controllable fluid actuated piston or the like pressure applying means adapted to exert a predominating thrust in a direction crosswise of the lifting bar axis while the aforesaid resilient means applies a door counterbalancing pressure lengthwise of said bar. By virtue of this arrangement, our toggle linkage when forced through a certain dead center position, is enabled to thrust both closed door sections snugly against and along their jambs so as to afford a rattle free and virtually weatherproof joint.

When said piston is operative in opening the door, our toggle linkage is forcibly carried through its dead center position by said piston and continued outwardly to swing the door into its outrigger position, where it may still be substantially counterbalanced and upheld by the lifting bar without reliance on piston thrust.

A reversal of the piston movement positively closes the door and reestablishes its sealing thrust against the door jams. Our remote control may comprise a manipulative valve adapted to subject one or the other ends of a double-acting cylinder to vacuum influence, the vacuum source then being preferably lodged in a suitable engine manifold commonly associated with a self-propelled vehicle. An equivalent electric motor or the like power driven means may likewise be resorted to.

A piston rod is pivotally attached to the interior of the upper panel and serves to bodily swing the suspended door about its master hinge. Provision has been made to automatically fold the linked lower panel upon the upper panel while the door is being raised into outrigger position. Such collapsed panels may herein be further raised to a relatively higher elevation by disconnecting certain elements of our actuating gear and then bodily raising the bottom end of said lifting rod into registry with a stop shelf which releasably retains the folded door panels in their upturned loading position. If desired, the lower panel may be similarly manipulated without recourse to any automatic folding means. In either event, the elevation of a pair of partially collapsed panels in the manner herein practiced, shifts their combined center of gravity toward the pintle of the master hinge so as to materially reduce the counterbalancing effort required to sustain the door in outrigger position. Such counterbalancing effort also corre-

spondingly reduces the piston thrust required to open the door.

The object of our invention is to provide for overhead door devices of the character indicated that can readily be incorporated into a vehicle body, garage or other doorway at moderate first cost without requiring extensive changes in the prevailing housing structure thereof. Disclosed herein are also other features of organization which facilitate the manufacture and more particularly adapt such door improvements for industrial purposes, all of which will hereinafter be more explicitly set forth. Reference is had to the accompanying one sheet of drawings which is illustrative of a certain embodiment of our devices, and in which

Fig. 1 represents an elevational rear end view of a vehicle body equipped with our improved sectional overhead door, this being here shown 20 raised in outrigger position.

Fig. 2 is a cross-sectional view taken along 2-2 of Fig. 1 and in which the door panels are depicted in full-lined closure position while alternative elevated panel positions are indicated in 25 dotted outline.

Referring now in detail to the drawing, this disclosure is representative of a closable van body, preferably comprising a pair of metal sheathed side walls such as 10 and a transverse top wall 11. 30 Such sheaths may be mounted upon a body framework comprising spaced rear corner posts or vertical door jambs 12 that may be rabbeted to constitute an inset door ledge. Adjacent upright side ribs such as 13 are also comprised in this latticed body framework. Cross rib members such as the rear sill 14 and the lintel or deck beam 15 may be similarly rabbeted to provide for an inset endless ledge that circumscribes the doorway. When closed, the exterior door 40 surface then falls into flush alignment with the tail end of the van to impart a neat trim thereto. The body framework may further include the usual side sills such as 16 mounting a floor board 17 thereon and which sills may rest in a conventional manner upon a pair of automotive chassis channels 18.

Our sectional door is provided with a rigid flat upper panel 20 of which a marginal edge may be pivotally suspended to the deck beam 15 by a 50 continuous piano or other type of master hinge 21. A weather strip fashioned from sponge rubber or the like, may be seated around the end-less jamb ledge of our doorway.

A winglike lower panel 23 may in turn, be linked 55 to the transverse free edge of said upper panel by the secondary hinges 24. Such pivotal connection is herein reversely disposed with respect to our prior disclosure so that an inward pressing of the upper panel toward its jambs will positively seat the depending lower panel. For long hauls, either of these closed panels may be latched or bolted in place, although our door actuating means when properly set, alone suffice to retain the door against inadvertent opening.

65 This sectional overhead door is designed to be swung outwardly and upwardly away from said jambs about its master hinge 23 into either the outrigger or erect positions, respectively represented in dotted outline in Fig. 2. To facilitate 70 the lifting of such door, the interior face of the upper panel carries an outstanding fulcrum bracket 25 of which the demountable pivot or toggle pin is designated 26. Said pin engages one end of a lifting bar 27 of finite length whose 75 depending end portion may extend downwardly

in substantial parallelism with the closed door. The lower bar extremity or toe is preferably carried beneath the floor level as shown and may be restrained against lateral tilt around the fulcrum 26 by a slotted guide plate 28. Said plate 5 may be provided with an offset stop lug or shelf-like ledge 29 whose purpose will presently be defined. As indicated in Fig. 1, it is preferred to employ dual control rods, respectively located closely adjacent to the respective body sides so as to conserve loading space and obviate an unbalanced lift upon the door.

A comparatively heavy door counterbalancing thrust may be exerted lengthwise of said lifting bar by a correspondingly massive laminated leaf 15 spring or a similar supplementary thrust applying agency 30, preferably installed beneath the floor level as shown. Such spring may however, be disposed above the floor level and wholly within the vehicle interior, such for example as the 20 substitute coil spring 31 depicted in dotted outline.

Intermediate its ends, the cited leaf spring may be pivotally supported upon a channel cross rod 32. The forward leaf end may rest against a 25 cross strap 33 or the like abutment, while the free rearward leaf end operatively engages the toe extremity of the depending lifting bar 27. The finite overall length given to this bar is such that when operatively interposed between the 30 agency 30 and the toggle fulcrum 26, said agency will maintain a follow-up thrust component lengthwise of the bar axis while the upper door panel moves between its closed and outrigger positions. During such travel, the path of said 35 fulcrum passes through its link alignment or dead center position designated 34, which subjects the spring 30 to maximum deflection.

After the toggle pin 26 passes inwardly beyond such critical point, said spring will cause the 40 upper panel to be snugly thrust against its jambs. By virtue of the interlocked disposition of the secondary hinge 24, the lower panel will be likewise retained in closed position.

In order to forcibly open the door as a unit 45 against such closure thrust, we provide for suitable remotely controlled actuating means. The present disclosure schematically embodies piston means for such purpose that may be intermittently reciprocated by motive fluid. As an instance, a separate air cylinder 35 for each lifting bar may be equipped with demountable heads of which one such is provided with a trunnion 36 supported by the deck and the other head has a 50 stuffing box 37. A piston 38 cooperates with a 55 rod 39 of which the free end may transversely engage the lifting bar at its fulcrum point 26, as shown.

Each cylinder end is equipped with separate feed tubes such as 40 and 41 which respectively 60 lead to a centralized control valve casing 42. A valve port 43 commands the head end tube 40 and an opposite port 44 commands the crank end tube 41. As will be understood, these ports may be spacedly disposed about a casing bore in which 65 is mounted the rotatable control valve or two way cock 45 having a manipulative lever 46. Said cock may be provided with a vent port 50 that communicates with the atmosphere and serves 70 to break a previously established vacuum in the air cylinder.

A reserve tank 47 may be installed in the manner schematically indicated in Fig. 2. This tank is in turn, piped at 48 to the engine manifold (not shown) or the like vacuum source. A 75

check valve 49 may be inserted in the pipe line 48 not only to prevent loss of any vacuum that may have been stored in said tanks, but from time to time exhaust the tank down to the limit of vacuum that may prevail in the manifold. Such charged tank is preferably located beneath the body floor and serves to activate the piston in the event the vehicle engine is shut down. Said valve together with its lever are intended 10 to be installed in the vehicle cab within easy reach of the driver.

Assuming the overhead door to be closed and its actuating gear to stand in the Fig. 2 position, then when the manipulative lever 46 is shifted 15 into its rightward full-lined position, this will place the tank 47 in communication with the head end tube 40. This in turn exerts a pull in the piston rod that yieldably holds the door panels shut because of equalized atmospheric air 20 that has been fed into the crank end tube through the registering vent port 50. Such piston effort is supplemented by a similar closing thrust moment afforded by the uplifted bar 27. The predominating magnitude of the door closure 25 effort supplied by said piston may be such that it becomes immaterial whether the bar contributes any substantial share thereto. In such instances, the closed door is adequately retained, although the fulcrum 26 may not be carried inwardly beyond its dead center position.

When the lever 46 is reversely shifted into its dotted position, a vacuum will then be set up in the crank end of the cylinder, which puts the piston rod under compression and brings about 35 an opening movement of the upper panel around its master hinge. In order to shorten the required stroke, the piston rod is operatively connected to the upper rather than to the lower panel, the resultant rod thrust being purposely 40 directed crosswise of the lifting bar axis.

When a toggle closure is employed, the air cylinder initially causes the free end of the leaf spring 30 to be depressed against a resilient counter moment. After the common fulcrum pin 45 26 has been forced through its dead center position 34, said spring will then serve as a counter-balancing agency that contributes to the lifting of said door toward its outrigger position. Such contributory effort permits of using a relatively 50 small air cylinder bore, this being particularly of importance when working with a manifold vacuum whose mean intensity is likely to be of a relatively low order. By its use however, no special air compressor or oil pump is required to 55 actuate the piston under remote control.

After the piston is fully urged toward its crank end, the upper panel of our overhead door will stand in its outrigger position shown in dotted outline. The linked lower panel may be allowed 60 to freely depend from its secondary hinges 24 and then be manipulatively shifted and latched out of the way into overlying relation to one face of the upper panel. It will be observed that while the upper panel is being elevated, the lower 65 panel swings inwardly toward the master hinge pintle and thereby reduces the counterbalancing effort required by the spring 30.

As an alternative, said lower panel may also be hooked up to automatically collapse upon 70 the upper panel by the use of a cable interconnection. As an instance, the panel cable 52 is shown threaded over a series of pulleys. One such pulley 54 may be mounted upon the interior face of the upper panel and the pintle of 75 another pulley 55 may be fixedly carried by the

jamb 12. When these pulleys are appropriately located, one cable end may be clamped at 56 to the interior face of the lower panel and the opposite cable end hooked to the upper panel as at 57. This cable system is arranged to automatically draw the swinging end of the lower panel 5 forwardly toward the upper panel when the latter is opened and to allow said lower panel to drop alignedly against the door jambs when the upper panel assumes its closure position. In such 10 closed door position, both linked panels will be snugly pressed and retained toward said jambs because of the described secondary hinge disposition.

In order to more adequately clear our over-head doorway for loading purposes and allow the door to assume erect position, its further elevation may be accomplished in several different ways. We prefer to provide for a simple detachable coupling 59 in the piston rod 39. By breaking this coupling and disengaging the cable hook 57, the upper panel is made free to swing about its master hinge into the fully upturned position indicated in dotted and dashed outline, the combined panel height being kept relatively low. 25 When the collapsed door panels are thus raised manually, the fulcrum pin 26 still remains in place and brings about a corresponding lift of the lower toe end of the non-extensible bar 27. The disposition of the shelflike ledge 29 is such 30 that the raised bar toe end is adapted to rest thereon and fixedly hold our door in its erect position. An equivalent abutment 29 may also cooperate with a fixed lug disposed intermediate the bar length. If preferred, the lifting bar 26 35 may also be made extensible in the manner more fully defined in our copending application.

After loading the van, the bar toe hereof may be kicked out of engagement from its ledge and dropped back upon the underlying leaf spring. 40 By again hooking up the cable system and engaging the piston rod coupling 59, our door actuating mechanism will be operatively reestablished. A single non-extensible lifting bar is herein made to serve as a combined door counterbalancing and retaining means adapted to sustain the door in two alternative elevated positions. The present devices are wholly free from sway with a change in the rate of vehicle travel, also from guide rods or cable suspended counter-weights such as commonly form part of a conventional overhead door assembly. The demountable bracket pin 26 allows one or both of the lifting bars 27 to be temporarily removed in 45 the event that the maximum of side clearance 50 space should be needed for loading purposes. In addition, our air cylinders are intended to be kept close to the deck so as not to encroach unduly upon effective loading space; if preferred, one or more of the cylinders may also be located 55 beneath the floor level and then be linked up to their cooperating fulcrum pin or pins in an equivalent manner.

It is thought the foregoing detailed disclosure will make evident to those skilled in this art, 65 other advantages inherent in our improved drive gear for overhead doors, it being understood that we reserve the right to incorporate equivalent means in any of our illustrative embodiments, all without departing from the spirit and scope of 70 our invention heretofore described and more particularly pointed out in the appended claims.

We claim:

1. A doorway including complementary vertical jambs and a transversely disposed deck beam, 75

in combination with an overhead door closing against said jambs and having a marginal edge hingedly suspended from the deck beam to allow of swinging the opened door away from both jambs into outrigger and erected positions, 5 a toggle linkage including a lifting bar of finite length of which one end region is operatively attached to the interior face of said door and the opposite toe end of which bar is guided, and 10 disconnectible counterbalancing means imposing a lifting thrust at the toe end region of said bar to counterbalance the raised door in outrigger position, there being abutment means associated with the toe end of said bar serving to uphold 15 the door when raised into its erected position and which bar in the last named position is operatively disconnected from the counterbalancing means.

2. A vehicle body of the enclosed type provided with a doorway including complementary vertical jambs and a transversely disposed deck beam, a sectionalized overhead door closing said doorway and comprising linked upper and lower panels that are counterbalanced and of which 25 the lower panel is foldable toward a face of the upper panel, said door having a free marginal edge hingedly suspended from the deck beam to allow of swinging the door outwardly away from both jambs from its closure position into outrigger position, actuating means including a lifting bar pivotally applied to the upper panel for moving said door between the aforesaid positions, and means serving to automatically fold said 30 panels upon each other when the door is moved 35 toward its outrigger position.

3. A doorway including complementary vertical jambs and a transversely disposed deck beam, in combination with an overhead door closing against said jambs and having a marginal edge hingedly suspended from the deck beam to allow 5 of swinging the opened door away from both jambs, actuating means comprising non-extensible lifting bar means of finite length of which one end region is pivotally adjoined to a face of the door, and counterbalancing means imposing 10 a thrust lengthwise of said bar to uphold the door in a partially open position, said lifting bar means including abutment means arranged to engage with and thereby uphold the opposite end 15 of said bar when the door is raised into a relatively higher elevation.

4. In a doorway including complementary vertical jambs and a transversely disposed deck beam, the combination of a sectionalized overhead door closing said doorway and comprising 20 linked upper and lower panels of which the lower panel is rendered foldable toward a face of the upper panel, said door having a free marginal edge hingedly suspended from the deck beam to allow of swinging the door outwardly away 25 from both jambs into outrigger position, a door counterbalancing agency, lifting bar means operatively interposed between one face of the upper panel and said agency, and flexible interconnecting means extending between said door and a 30 stationary point serving to automatically fold the lower panel toward the upper panel when said door is swung into outrigger position.

CHARLES H. CLARK
ROBERT C. HOLLISTER.
